UNITED STATES PATENT OFFICE

113,823

DESIGN FOR A DRESS

Albert Ruchman, New York, N. Y.

Application January 11, 1939, Serial No. 82,272

Term of patent 3½ years

To all whom it may concern:

Be it known that I, Albert Ruchman, a citizen of the United States, residing in the city of New York, in the county of New York and State of New York, have invented a new, original, and ornamental Design for a Dress, of which the following is a specification, reference being had to the accompanying drawing, forming part thereof.

Fig. 1 is the front view of a dress showing my design;

Fig. 2 is a rear view of the dress shown in Fig. 1; and

Fig. 3 is an enlarged fragmentary view of the dress shown in Fig. 1 illustrating one of the quilted pockets in detail.

The characteristic feature of my design resides in the combination on the dress disclosed of the specific pocket members which are quilted as shown.

I claim:

The ornamental design for a dress, substantially as shown and described.

ALBERT RUCHMAN.
